UNITED STATES PATENT OFFICE.

JAMES G. HARTER, OF BERWICK, PENNSYLVANIA.

WRENCH.

1,152,727.

Specification of Letters Patent.

Patented Sept. 7, 1915.

Application filed January 21, 1915. Serial No. 3,621.

To all whom it may concern:

Be it known that I, JAMES G. HARTER, a citizen of the United States, residing at Berwick, in the county of Columbia and State 5 of Pennsylvania, have invented certain new and useful Improvements in Wrenches, of which the following is a specification.

This invention relates to wrenches and has for its primary object to provide a 10 wrench which is readily disassembled and assembled.

Another object is to provide a wrench, the working parts of which are inclosed.

A further object is to provide pivoted 15 socket holding members and to provide novel means for holding said members against accidental separation.

With these and other objects in view the invention consists in the novel features of 20 construction, combination and arrangement of parts as will be hereinafter more fully described, illustrated in the accompanying drawings and claimed.

In the drawings: Figure 1 is a plan view 25 of the improved wrench; Fig. 2 is an edge view; Fig. 3 is a horizontal sectional view through the head; Fig. 4 is a section on the line 4—4 of Fig. 1.

Referring to the drawings by numerals, 1 30 designates the handle which is provided at its inner end with an enlarged rectangularly-shaped portion 2, lugs 3 being formed on the outer faces of the portion 2 for a purpose which will hereinafter be described. 35 The enlarged portion 2 is bifurcated as will be recognized upon reference to Fig. 4, so as to provide for the reception of an actuating pawl that will be presently described.

A pair of substantially semicircularly- 40 shaped sockets that are provided for holding members 4 and 5 are pivoted together as at 6 and their free ends are provided with offset extensions 7 and 8, respectively. A channel or groove 9 is formed in each of 45 the members 4 and 5, which is adapted to receive a tongue 10 formed on the circumferential edge of a socket member 11.

In assembling the parts referred to, the 50 socket 11 is first arranged between the members 4 and 5, after which the sleeve 13 is moved into place about the extensions 7 and 8. When the sleeve 13 assumes this position the socket 11 will be securely retained in 55 revoluble relation to the members 4 and 5. The enlargement 2 on the handle 1 is now brought into position between the extensions

7 and 8 so that the lugs 3 bear against the sleeve so as to retain the latter in a rigid position. The bolt 12 is passed through the extensions and the adjacent portion of the 60 enlargement on the handle so as to retain the handle in a firm position. When the parts assume this position the pawl 14 will be yieldingly held in engagement with certain of the notches 15 in the socket. Consequently when the handle 1 is oscillated the pawl will cause the rotation of the socket 65 in a desired manner.

A pawl 14 is slidably arranged between the extensions 7 and 8 and the bifurcated 70 end of the portion 2. This pawl is normally held in engagement with notches 15, formed in the edge of the socket 11, by means of a coil spring 16 which bears 75 against the inner face of the pawl 14 and handle 1. An opening 17 is formed in the socket 11 to receive the heads of bolts or nuts to be turned. It will be seen that by engaging the socket 11 with a bolt and exerting pressure upon the handle 1, the socket 80 11 will be caused to rotate by means of the pawl 14. Also that the parts of the wrench are easily assembled or disassembled. If desired, the handle 1 may be cored as shown at 18 to lessen the weight thereof. Also, if 85 desired, oil or any other suitable lubricant may be placed in this bore to supply a lubricant to the working parts of the wrench.

From the foregoing description taken in connection with the accompanying drawings 90 it is thought that the construction and operation of the device will be clearly understood and while I have herein shown and described one specific form of my invention I do not wish to be limited thereto, except 95 for such limitations as the claims may import.

What is claimed is:—

1. A wrench of the character described comprising a pair of substantially semi-circular holding members, one end of said members being pivotally connected, extensions carried at the free ends of said members, each of said members provided with a groove, a socket, an enlarged portion on said 100 socket for engagement with said grooves, said socket being retained between said members, a sleeve arranged about said extensions to retain said members in engagement with said socket, a handle portion, an 105 enlargement on one end of said handle portion, said enlargement extending between 110

said extensions, means connecting said enlargement and said extensions, a pair of outstanding lugs on said enlargement engaging said sleeve and retaining the same in a rigid position, said enlargement being bifurcated, a pawl mounted between the braces of the bifurcation in said enlarged portion, and a spring to retain said pawl in engagement with said socket, as and for the purpose set forth, and described.

2. A wrench of the character described comprising a pair of substantially semi-circular holding members, one end of said members being pivotally connected together, 15 extensions formed at the free ends of said members and extending in substantially parallel relation to each other, a socket arranged between said members, a sleeve

mounted on said extensions to retain said members in engagement with said socket, a handle portion having an enlargement formed at one end, said enlargement fitting between said extensions, means connecting said enlargement and said extensions, a pair of lugs on said enlargement engaging said sleeve, to retain the same in a rigid position, and a pawl carried by said enlargement to actuate said socket as and for the purpose set forth and described.

In testimony whereof I affix my signature 20 in presence of two witnesses.

JAMES G. HARTER.
